UNITED STATES PATENT OFFICE

96,605

DESIGN FOR A CONDIMENTS SET OR THE LIKE

Samuel Haslam, Attleboro, Mass.

Application June 15, 1935, Serial No. 57,286

Term of patent 3½ years

To all whom it may concern:

Be it known that I, Samuel Haslam, a citizen of the United States, residing at Attleboro, in the county of Bristol and State of Massachusetts, have invented a new, original, and ornamental Design for Condiment Sets or the like, of which the following is a specification, reference being had to the accompanying drawing, forming part thereof.

The figure is a perspective view of a condiment set showing my new design.

I claim:

The ornamental design for a condiment set or the like, as shown.

SAMUEL HASLAM.
